(57) CLAIM

The ornamental design for an egg shaped handheld computing device, as shown and described.

DESCRIPTION

FIG. 1 is a front elevational view of an egg shaped handheld computing device in accordance with the invention.

FIG. 2 is a right side elevational view of the egg shaped handheld computing device of FIG. 1; and,

FIG. 3 is a left side elevational view of the egg shaped handheld computing device of FIG. 1.

The top, rear and bottom sides that cannot be seen in the Figures are substantially similar to the front elevational view shown in the drawing. The broken lines showing a floral pattern in the Figures are for illustrative purposes only and form no part of the design.
